United States Patent Office

Des. 204,293
Patented Apr. 5, 1966

204,293

PLATE OR SIMILAR ARTICLE

Shigeru Masuda, 2185 Central Road, Apt. C,
Fort Lee, N.J.

Filed Jan. 8, 1965, Ser. No. 83,349

Term of patent 3½ years

(Cl. D44—15)

FIG. 1.

FIG. 2.

The figure is a plan view of a plate or similar article showing my new design, a portion of the design being shown between dotted lines and a repeat portion being shown between dot-and-dash lines.

I claim:

The ornamental design for a plate or similar article, substantially as shown and described.
